UNITED STATES PATENT OFFICE.

JOHN S. TRAVIS, OF PATERSON, NEW JERSEY, ASSIGNOR TO THE
LAMOND & ROBERTSON COMPANY, OF SAME PLACE.

DESIGN FOR A RUG.

SPECIFICATION forming part of Design No. 27,967, dated December 7, 1897.

Application filed October 29, 1897. Serial No. 656,859. Term of patent 3½ years.

To all whom it may concern:

Be it known that I, JOHN S. TRAVIS, a citizen of the United States, residing at Paterson, in the county of Passaic and State of New Jersey, have invented and produced a new and original Design for Rugs; and I do declare the following to be a full, clear, and exact description of the same, reference being had to the accompanying photographs, forming a part thereof, which represent—

A rug upon which is the representation of a large St. Bernard dog lying upon a rug and a sleeping child reclining against the dog. Around the rug proper is a plain border in side of which is an ornamental border through the upper right-hand and left-hand corners

of which depend bunches of roses. The rug upon which the dog and child are represented to be reclining has ornamental borders and fringe. A toy doll is shown as having dropped ²⁰ from the hand of the sleeping child.

This design is to be woven in different colors into rugs.

I claim—

The design for a rug substantially as herein ²⁵ shown and described.

In testimony whereof I affix my signature in presence of two witnesses.

JOHN S. TRAVIS.
